UNITED STATES PATENT OFFICE.

JOHN O. DE WOLF, OF CAMBRIDGE, MASSACHUSETTS.

APPARATUS FOR MAKING PRINTING-PLATES.

No. 884,369.

Specification of Letters Patent.

Patented April 14, 1908.

Application filed February 10, 1908. Serial No. 415,123.

To all whom it may concern:

Be it known that I, JOHN O. DE WOLF, a citizen of the United States, residing at Cambridge, in the county of Middlesex and State 5 of Massachusetts, have invented an Improvement in Apparatus for Making Printing-Plates, of which the following description, in connection with the accompanying drawings, is a specification, like letters on the 10 drawings representing like parts.

My invention has for its object the production of an apparatus to save time in making printing plates for the modern newspaper office, although it will be understood that its 15 range of usefulness is much more extensive. In the use of this apparatus I accomplish accuracy, neatness, economy and various other advantages, which will appear in the course of the more detailed description.

20 In modern newspaper work by far the most important item is to save time in getting out the printed page, and accordingly every energy and facility of the entire plant, regardless of expense are commonly bent to 25 the one object of speed or economy of time; and as at present practiced the most aggravating delay usually occurs in the stereotyping room. It is customary now first to set the type with a linotype machine, then make 30 a papier mâché matrix therefrom and when the latter has hardened, bend it to the proper curvature within a mold or casting box, clamp it in place, closing the casting box, and then pour the molten metal. After the 35 latter has cooled sufficiently to permit of opening the mold, the casting box is opened, the matrix is unlocked and is then stripped off. The stereotyped plate is next taken out, or, in some cases, both the plate and 40 matrix are removed together and afterwards separated. Then the stereotype plate is finished, this process usually consisting of removing the surplus metal at the edges and ends, properly finishing the same 45 so that they will fit on the cylinder of the printing press, and finally the back of the plate is shaved to a true form. The exact order of these operations varies somewhat, but the above sets forth with practical correctness the operations and amount of work 50 commonly employed. It will be seen that time is wasted at each operation in waiting for the completion of one part of the process before commencing the next part and that 55 also much time is lost in waiting for the metal to cool and in shaving the back to fit

the cylinder, etc. Accordingly it is my object to save all this wasted time.

In its preferred embodiment, as herein shown, my apparatus consists of means for 60 delivering metal in an impressionable condition against a matrix by which said impressionable metal is at once impressed, the pressing of the matrix into the plastic impressionable surface of the type metal pro- 65 gressing evenly and continuously from one edge of the matrix to the other, and, while the matrix is being pressed into the metal at one region, the metal is being permanently cooled and set at the previously impressed 70 region, and the matrix is being stripped from the metal further along where the latter has become entirely set.

I do not herein claim the method or the article as these are expressly reserved for sep- 75 arate applications.

In the most complete embodiment of my invention I provide means for bringing together progressively the moldable metal, *i.e.*, the stereotype metal rendered locally im- 80 pressible by heat, and the matrix in the presence of a chilling medium, so that the metal, delivered either molten or semi-molten, obtains its form or type impression from the matrix along a progressive line, or 85 narrow region, and is instantly caused to set. I prefer to employ as thin a layer of metal as possible in order that it may change from a freely fluid or highly molten condition to a plastic or impressionable condition instantly 90 and thereby receive its impressed shape, and then cool or set etc. with the greatest rapidity and accuracy. This enables me to eliminate in the highest degree the danger of shrinking and inaccuracy which has hereto- 95 fore been due to the employment of a large body of metal; and because of this feature of my invention I have succeeded in eliminating entirely the necessity of shaving the back of the plate to fit the press. To this end I em- 100 ploy a previously prepared back capable of receiving said thin face of proper metal, such as stereotype metal.

In the accompanying drawings, in which I have shown one embodiment of my invention, Figure 1 is a central longitudinal section thereof; Fig. 2 is a similar sectional view of a fragment thereof considerably enlarged; Fig. 3 is a sectional detail similar to Fig. 1 excepting that it shows the position of the parts 105 as they are delivering the completed plate 110 and ready to begin operations in making the

next plate; Fig. 4 is a view in end elevation of the parts shown in Fig. 3; Figs. 5 and 6 are longitudinal sectional views of the water cooled portions of the apparatus, Fig. 5 being a substantially vertical section and Fig. 6 a nearly horizontal or oblique section for showing the various cooling passages and also showing the shape of the edges, etc., of the compound printing plate as it is being formed.

10 Mounted on a suitable base or frame 1 is a rotary cylinder 2 journaled at 3 in heavy uprights 4 and operated by any convenient means by a worm 5 and worm wheel 6 driven by an electric motor or other source of power 15 Fig. 5, adapted to be automatically tripped by a lug 9 and latch 10 or any other usual or preferred tripping mechanism for automatically stopping the machine. At the lower right-hand corner or side of the apparatus, see Fig. 1, 20 is a water-cooled concave surface 11 for coöperating with the cylinder 2, and at the left thereof extending between the uprights 4 is a stripper blade or other stripping means 12 just above a transfer table 13 pivoted at 14 25 to the base 1 and normally held horizontal by a latch 15 operated by a handle 16, and adapted to be tilted into the dotted position Fig. 1, for the purpose of delivering the 30 stripped matrix to a conveyer 17 so that it will be in position for the operator to replace it in the machine for making a separate printing plate. The matrix 18 is placed in a delivery device or hopper 19, which I face 35 with asbestos or other shield 20 for preventing the same from being injured by the heat which is in front thereof.

As is well known, type metal will stiffen or chill to an impressionable condition almost 40 instantly if caused to strike a cooled surface in a thin layer or sheet, and hence, as it is much more convenient to deliver the metal in a fluid or actual molten condition and depend upon the cooling effect of the chilled metal of 45 the rotary cylinder to check the highly fluid condition of the metal and change it to the doughy plastic or sluggishly molten condition which is necessary to render it impressionable in order that it may receive the im- 50 press of the matrix when the latter is pressed against it, I have shown the metal 21 as delivered in a highly fluid condition from a nozzle 22 of a pipe 23 through which the metal is pumped or otherwise delivered from a suitable source 24, being herein shown as delivered 55 by gravity, a valve 25 controlling the inlet, and gas jets or other suitable heating means 26 being provided for maintaining the pipe 23 properly heated.

60 Any convenient means may be provided for cooling the cylinder 2, the latter being herein shown as having a water-jacket or suitable cooling means 27 over that portion 65 against which the molten metal is delivered or caused to contact for producing the chill-

ing effect thereon, as above explained. At the forward end of the cooled or water-jacketed portion of the cylinder 2 I provide a transverse block 28 which also performs the office of a dam or stop for the metal, as will presently be explained, over which the forward edge 29 of the matrix is adapted to be bent and clamped automatically by any suitable mechanism, such for instance as is commonly employed in printing presses, being herein shown as consisting of clamps 30 on a rod 31, provided externally with a gear 32 operated by a toothed sector or rack 33 pivoted at 34 to the cylinder and held under downward tendency by a spring 35 as well as 75 by its own gravity, said sector rack having a shouldered engaging surface 36 for traveling on a cam ring 37 which has an incline 38 at another portion thereof, see Fig. 4. Thus when the cylinder is just reaching the position shown in Fig. 3, or rather is just passing forward from the position shown in Fig. 3, the shoulder 36 drops from the shoulder 39 and thereby gives an instant rotary movement to the clamps 30, so that the clamping ends of the latter move in the path shown in dotted lines in Fig. 3 and operate to clamp the forward edge 29 of the matrix tightly over the block 28 as shown in Figs. 1 and 2, holding the same tightly until said part 36 reaches the 85 part 38 of the cam ring, whereupon the clamps are automatically rotated in an opposite direction, thereby releasing the matrix, which because of its comparatively stiff nature and the fact that it has been bent 90 over the angular block 28, springs out away from said block, to be engaged by the stripper 12. This will be explained more at length presently. The cavity 40 in the concave face 11 is beveled at its ends 41 as 105 clearly shown in Fig. 6, thereby accurately forming the plate to its finished shape. The water jackets are supplied with water by any well-known means, pipes 42 being indicated for the stationary water-jacket and axial pipes 43 being indicated for the cylinder jacket. While I do not intend to limit my invention, in all cases, to the employment of the extra thin layer or facing of type-metal 110 previously mentioned, I prefer to employ 115 said back or backing and accordingly the receiving surface of the cylinder is cut away at 44 to receive the back 45 on which the type face is secured and impressed, said cut-away portion 44 coöperating with the recess 40 in 120 the concave shaper or receiving surface. Coöperating with the recess 44 of the cylinder is a stripping mechanism, which may be of any convenient kind, being herein shown as consisting of stripper heads 46 carried by 125 rods 47 reciprocated by bell cranks 48 operated by a shaft 49 located in the cylinder to aline at proper intervals with a plunger 50 pivoted at 51 to a hand lever 52 pivotally mounted at 53 on the frame of the machine. 130

The back has previously been prepared with perfect accuracy and provided with suitable means for permitting the metal to be automatically united thereto, as by entering holes 5 54 or dove-tailed grooves, scorings, or permitting any other mechanical bond, on the back 45, or the back may be of such consistency as to be slightly fused or amalgamated with the covering surface of type metal by 10 reason of the heat of the latter when poured against said back in a molten condition. I wish it understood also that my invention includes the impressing of the type metal whether the latter is united to a back or constitutes the entire plate and whether it is delivered in a molten condition or not, and whether the metal is rendered impressionable by being originally entirely fluid and then partially cooled at the local region 20 where it is being impressed or by being originally set or hard and then simply softened at the local region where it is being impressed. In either case the use of a previously prepared backing is advantageous as it permits 25 all the necessarily slow back-forming part of the procedure to be performed previously, when time is not vital. Those skilled in the art will readily understand that the need for haste all occurs after the matrix is ready, so 30 that whatever work can be done towards the final finished plate previous to my impressing operation is of decided advantage in point of time.

The operation of my apparatus is as follows: Let it be supposed that the machine is 35 in the position shown in Fig. 3, the operator takes a back 45 which has been previously prepared at any time convenient, as above explained, and this back 45 he places on the 40 recess 44 of the cylinder in the position shown in Figs. 1 and 4. He then places a matrix 18 in the delivery device 19 so that its forward end is about in the position shown in Fig. 3. Thereupon he throws the starting lever 9, 45 and the moment that the cylinder has rotated sufficiently to bring the matrix and cylinder together the matrix is instantly clamped automatically by the dogs 30 which swing from the position Fig. 3 to the clamping position Figs. 1 and 4, so that thereafter the matrix and back are moved forward together by the cylinder. Meanwhile, the instant that the clamping of the matrix takes 50 place the molten type - metal 21 (herein 55 shown in the preferred embodiment of my invention as restricted to the thin sheet-like, minimum amount for the facing or outside coat for the back 45) is permitted to flow. At this instant the top shoulder or ledge of 60 the transverse block 28 is in position just beneath the nozzle 22, so that it acts as a dam to compel the momentary halt of the metal, and as this halting of the metal is against the chilled surface of the back 45 (or if no back is 65 employed, then against the chilled surface of

the cylinder itself), the highly fluid condition of the metal is instantly eliminated, i. e., the metal is instantly stiffened sufficiently to prevent its flowing over and beyond said dam, and sufficiently to cause it to form into a thin plastic, moldable or impressionable facing sheet on the front of the back 45, with the result that when this facing of partially set stereotype metal immediately thereafter reaches the matrix it is in a condition to receive the imprint of the latter as the matrix is forced into compressing engagement with said impressionable metal. In this manner the permanent impress desired is instantly and progressively effected throughout the 70 entire plate inasmuch as the rotary forward movement of the metal is continuous. The metal is rendered impressionable at the local region at or immediately prior to engaging with the matrix and then as the matrix 75 presses its molding face or front face into the soft impressionable metal the latter is immediately chilled still further, until, when it reaches the outgoing end of the apparatus, it is entirely and permanently set so that the 80 matrix may be stripped off leaving the finished stereotype printing plate. The heated impressionable portion of the plate is 85 preferably maintained localized to the few transverse lines of matrix at the upper end of 90 the opening between the forming surface 11 and the back 45, said locally impressionable condition being progressively shifted rearwardly as the plate advances, until it has 95 been shifted over the entire plate, which has 100 then been entirely impressed by the matrix. In the same manner the cooling of the plate 105 progressively shifts over the entire area of the impressed plate. The moment that the 110 impression in the softened metal is made the advance metal and the adjacent parts are at once cooled by the water-jacketed portions of the cylinder and the mold 11. My apparatus maintains the metal in a softened or sluggishly molten condition at the initial 115 contacting point of the back, metal and matrix, where the metal is simultaneously molded and set in permanent form and this is progressively accomplished over the entire surface. I prefer to move simultaneously 120 the matrix, metal and back, although I wish it understood that my invention includes any means for accomplishing the movement or progress of the heated impressionable region, the cooling region and the forming region, 125 with relation to the matrix, the idea being to provide means for causing the forming of the stereotype progressively over the matrix, or in other words, to render the metal locally impressionable by heat and progressively shift said local condition over the required area of the matrix; at the same time that said locally heated condition with a localized cooling condition, all until the entire 130 plate has been impressed and cooled or set.

As the plate is being thus impressed and shaped by the matrix 18 and mold 11 along one narrow area or line thereof, the matrix and the same plate are being elsewhere separated from each other. As shown, where all the parts move together, the cylinder 2 continues rotating forward until the cam surface 36 strikes the surface 38, which thereupon releases the clamping dogs 30 from the forward end of the matrix and the latter, because of its inherent stiffness, springs out away from the block 28 in position to be caught automatically by the stripped blade 12, which operates to remove the matrix progressively from the lower end of the printing plate whose upper end is still being impressed and formed. The operation is continuous, without any halting at any point. When the cylinder has arrived at approximately the position shown in Fig. 3 it is preferably automatically stopped by the tripping device 9 or any other suitable stopping mechanism, and the operator then pushes in the lever 52, which raises the stripped heads 46, thereby lifting the completed plate to be carried to the printing press. As the plate has been formed with an impressed surface, as distinguished from a cast surface, and as said surface is thin and its permanent setting begins when it is still under pressure (said pressure being herein accomplished by the wedging of the matrix into pressing engagement with the impressionable metal, thereby forcing the irregularities of the matrix into the soft face of the metal) there is no resulting unevenness due to shrinkage or shifting in position of the metal (as is invariably the case in ordinary casting), and also for the same reason no subsequent shaving of the metal is required in order to bring it to the proper thickness. And where the previously prepared back is employed the necessity for shaving the back is also done away with as the two parts of the composite plate have been formed together as they have been moved along in unison.

I wish to emphasize the fact just mentioned, that the impressing and cooling of the metal takes place while the metal and matrix are being pressed toward each other in the act of accomplishing the impressing of the printing surface into the impressionable metal. This is one of the radically new and essential features of my invention which distinguishes it from what is commonly known in the art as casting. While it may be accomplished in various ways, I prefer to accomplish it by the gradual movement of the matrix forward into the metal, the concave surface 11, at least in its upper portion, being for this reason very slightly eccentric to the opposite surface of the cylinder 2, so that the matrix is moved perpendicularly into the softened, but not liquid, metal, being thereby

forced into the metal delicately, accurately and yet unyieldingly as it is pulled or caused to slide over the massive unyielding support and guiding member 11. This gives exceedingly sharp definition; which is due no doubt to this compressing of the metal while cooling, or in other words, to the perpendicular impressing of the matrix into the metal when the latter is in an impressionable condition. As the molding or impressing is done progressively, the metal does not have to flow as heretofore a long distance in a thin mold, and this arrangement make it possible and feasible to cast a thin and perfect face upon the prepared back.

My apparatus and method of progressive impressing and simultaneous cooling prevent the cooling strains and distortion of the finished plate which have taken place in the making of printing plates hitherto when a large area has been cast and then the same large area cooled at all points at once.

By the term "impressing" I mean to distinguish from casting, *i. e.* the metal is rendered impressionable or plastic in the sense that when its surface is pressed an imprint is left, as a seal ring is impressed into sealing wax, for instance, and when the metal is rendered thus impressionable it is impressed by the matrix by relatively moving the metal and the matrix perpendicularly toward each other so that the matrix presses into the softened or impressionable metal. This results in leaving a permanent, clean cut impress in the plastic surface of the impressionable metal. To accomplish this it is necessary that the matrix shall have an absolutely unyielding back-support, such as is provided by the concave surface 11, in order that the necessary pressure may be applied to the softened surface of the type metal to enable the matrix to press its imprint into the partially formed plastic plate as a signet ring impresses the sealing wax above mentioned.

I wish to make the distinction clear as to the difference between impressing and casting, as the latter term is commonly used in the art, inasmuch as my invention does not relate to the progressive formation of the plate, considered alone, as the progressive formation of a plate by ordinary casting (*i. e.* when the metal is in a fluid or readily flowing condition) is old in the printers art (see for example patents of Goodale, 155,609, October 6, 1874, and Lyman 315,045, April 7, 1885) but relates to the progressive formation of the plate by causing the metal to assume an impressionable or plastic condition capable of receiving an imprint or impress and then applying the matrix to said metal by such a movement and direction that the matrix presses into the metal with a forcible pressure, as distinguished from simply receiving the molten metal as in ordinary casting. The matrix is forced into the plastic

doughy surface of the impressionable metal and hence gives extremely sharp definition, whereas when fluid metal flows freely into the cavities of a mold such as a matrix, it not only fails to fill accurately and uniformly all the corners of the cavity, depending somewhat on the direction in which the metal is permitted to flow, but when the metal shrinks upon subsequently cooling, it results in a lack of proper definition. My apparatus, not dealing with the metal in the condition of ordinary casting and not accomplishing "casting", produces practically perfect plates having extremely sharp and accurate definition, simply because the metal is impressed by the matrix as distinguished from being cast by pouring it into a mold cavity which it is permitted to fill as best it may in the ordinary manner of casting.

20 As already stated, it will be understood that my invention is capable of various modifications and that I am not limited to the details herein set forth except as otherwise specified in the claims.

25 Having described my invention, what I claim as new, and desire to secure by Letters Patent is:

1. An apparatus for making printing plates, comprising mechanism for juxtaposing a matrix and plate material, means for rendering said plate material locally impressionable, means coöperating with said above means for progressively shifting said local condition over the required area of the plate material, and means for simultaneously and progressively pressing the matrix into said plate material at the region thus rendered locally impressionable.

2. An apparatus for making printing plates, comprising mechanism for juxtaposing a matrix and plate material, means for rendering said plate material locally impressionable, means coöperating with said above means for progressively shifting said local condition over the required area of the plate material, means for simultaneously and progressively pressing the matrix into said plate material at the region thus rendered locally impressionable, and means for progressively cooling the plate as it is impressed.

3. An apparatus for making printing plates, comprising mechanism for juxtaposing a matrix and plate material, means for rendering said plate material locally impressionable, means coöperating with said above means for progressively shifting said local condition over the required area of the plate material, means for simultaneously and progressively pressing the matrix into said plate material at the region thus rendered locally impressionable, means for progressively cooling the plate as it is impressed, and simultaneously operating means for progressively stripping the matrix from the plate as it is cooled.

4. In an apparatus for making printing plates, means for impressing the plate with the matrix at one portion thereof, and means for simultaneously stripping the matrix from the plate at another portion thereof.

70 5. In an apparatus for making printing plates, means for forming and impressing a plate with the matrix at one portion thereof, and simultaneously operating means for stripping the matrix from the plate at another portion thereof.

75 6. In an apparatus for making printing plates, mechanism for progressively forming and impressing the plate with the matrix, and means for progressively stripping the matrix from the impressed plate, all as a continuous operation.

80 7. In an apparatus for making printing plates, means for removably receiving a previously formed back, means for applying thereto a surface layer of plate metal, means for rendering said plate metal locally impressionable, and means for simultaneously impressing the surface thereof with the matrix.

85 8. In an apparatus for making printing plates, means for removably receiving a previously formed back, means for applying thereto a surface layer of plate metal, means for rendering said plate metal locally impressionable, means for simultaneously impressing the surface thereof with the matrix, and means, operating while said impressing by the matrix is proceeding, to begin stripping off the matrix.

90 9. In an apparatus for making printing plates, means for removably receiving a previously formed back, means for applying thereto a surface layer of plate metal, means for rendering said plate metal locally impressionable, means for simultaneously impressing the surface thereof with the matrix, and means for progressively cooling the impressed surface.

100 10. In an apparatus for making printing plates, mechanism for relatively moving, in progressive forming proximity, a matrix and a layer of type material in an impressionable condition, including means for pressing the matrix perpendicularly into the impressionable material, and means for simultaneously cooling said material as it is being formed.

110 11. In an apparatus for making printing plates, means to move a matrix forward, means to deposit thereon progressively under pressure a layer of type material, including means for bringing said material to an impressionable condition as the matrix moves, and means for cooling the deposited layer to a permanently set condition while the matrix is still moving.

120 12. In an apparatus for making printing plates, means to move a matrix forward, means to deposit thereon progressively under pressure a layer of type material, including means for bringing said material to an im-

6
pressionable condition as the matrix moves, means for cooling the deposited layer to a permanently set condition while the matrix is still moving, and means for stripping 5 apart said set layer and matrix while still moving.

13. In an apparatus for making printing plates, means for relatively moving a matrix and metal in an impressionable condition in 10 such relation to each other as to impress the surface of the metal with the matrix, and means to strip the matrix from the cooled plate during said movement.

14. In an apparatus for making printing plates, means to apply a matrix progressively over the surface of metal reduced to an impressionable condition by heat, temperature-controlling means to bring said metal to said impressionable condition, means for immediately cooling the metal after its surface is 20 so impressed, and means to compress the metal and matrix together while cooling.

15. In an apparatus for making printing plates, means, including a matrix, to form 25 progressively a printing face on a removable back previously prepared, and means to simultaneously remove the matrix from the completed portion of the face without waiting for the complete forming of the entire printing face of the plate.

16. In an apparatus for making printing plates, a cylinder, means thereon for positioning and retaining a previously prepared back for a printing plate, a concave mold 35 operating with said cylinder to form between the front face of said back and said mold a metal-receiving cavity, operating means to rotate said cylinder and back, and means to simultaneously feed in with the moving back 40 a matrix against said mold and a surface metal in an impressionable condition between said matrix and back, the aforesaid mechanism including means to compress said metal between the cylinder and matrix.

45 17. In an apparatus for making printing plates, a cylinder, means thereon for positioning and retaining a previously prepared back for a printing plate, a concave mold 50 operating with said cylinder to form between the front face of said back and said mold a metal-receiving cavity, operating means to rotate said cylinder and back, and means to simultaneously feed in with the moving back

a matrix against said mold and a surface metal in an impressionable condition between said matrix and back, said mold having a portion of its concave surface slightly eccentric to said cylinder and back for compressing the metal between the cylinder and matrix, as the cylinder, back, and matrix 60 move forward with relation to said concave mold.

18. In an apparatus for making printing plates, a cylinder, means thereon for positioning and retaining a previously prepared 65 back for a printing plate, a concave mold co-operating with said cylinder to form between the front face of said back and said mold a metal-receiving cavity, operating means to rotate said cylinder and back, means to simultaneously feed in with the moving back a 70 matrix against said mold and a surface metal in an impressionable condition between said matrix and back; the aforesaid mechanism including means to compress said metal between the cylinder and matrix, and said mold including means to hasten the cooling of the metal.

19. In an apparatus for making printing plates, a cylinder, means thereon for positioning and retaining a previously prepared 80 back for a printing plate, a concave mold co-operating with said cylinder to form between the front face of said back and said mold a metal-receiving cavity, operating means to 85 rotate said cylinder and back; means to simultaneously feed in with the moving back a matrix against said mold and a surface metal in an impressionable condition between said matrix and back, the aforesaid mechanism 90 including means to compress said metal between the cylinder and matrix, cooling means to hasten the cooling of the metal, said operating means maintaining constant forward movement, and automatic means 95 operating when the forward portion of the plate is properly cooled to progressively remove the matrix therefrom.

In testimony whereof, I have signed my name to this specification, in the presence of 100 two subscribing witnesses.

JOHN O. DE WULF.
